US00D800087S

(12) **United States Design Patent** (10) **Patent No.:** **US D800,087 S**
(45) **Date of Patent:** **** Oct. 17, 2017**

(54) **COMPACT CALL STATION**

(71) Applicant: **TALK-A-PHONE CO.**, Niles, IL (US)

(72) Inventors: **Samuel Shanes**, Highland Park, IL (US); **Clarence Wong**, Chicago, IL (US); **Khushroo Kali Patel**, Park Ridge, IL (US); **Jordan Karol**, Chicago, IL (US); **Joshua Ryan Skorich**, Lombard, IL (US); **Michael Douglas Prince**, Chicago, IL (US); **Tong Jin Kim**, West Lafayette, IN (US); **Christian Kulujian**, Chicago, IL (US)

(73) Assignee: **TALK-A-PHONE COMPANY**, Niles, IL (US)

(**) Term: **15 Years**

(21) Appl. No.: **29/539,219**

(22) Filed: **Sep. 11, 2015**

(51) **LOC (10) Cl.** **14-03**

(52) **U.S. Cl.**

USPC **D14/159**

(58) **Field of Classification Search**

USPC ... D14/159, 140, 140.1, 140.7, 140.8, 141.2, D14/142, 146-151, 158, 188, 217, 240, D14/243, 245, 247, 248, 251, 258, 299, D14/329; D13/123, 162, 164, 168, 173, D13/177, 184, 199; D10/106.1, 106.9

CPC H04M 1/00; H04M 1/02; H04M 1/0291

(57) **CLAIM**

The ornamental design for a compact call station, as shown and described.

DESCRIPTION

FIG. 1 is a front perspective view of a compact call station of the new showing the design;

FIG. 2 is another front perspective view of the compact call station showing the design;

FIG. 3 is a rear view of the compact call station showing the design;

FIG. 4 is a left-side view of the compact call station showing the design;

FIG. 5 is a right-side view of the compact call station showing the design;

FIG. 6 is a top view of the compact call station showing the design; and,

FIG. 7 is a bottom view of the compact call station showing the design.

The broken lines in the drawings depict portions of the compact call station that form no part of the claimed design.

1 Claim, 5 Drawing Sheets
